ATTORNEYS.

UNITED STATES PATENT OFFICE

EDWARD B. HESS, OF ORLANDO, FLORIDA, ASSIGNOR TO ROYAL TYPEWRITER COMPANY, INC., OF NEW YORK, N. Y., A CORPORATION OF NEW YORK

TYPEWRITING MACHINE

Application filed January 5, 1931. Serial No. 506,807.

This invention relates to new and useful improvements in typewriting machines generally, although more particularly to typewriting machines for writing on cards or 5 other flat work sheets.

In writing on cards with the ordinary commercial machine, it is necessary to roll the cards around the cylindrical platen. This rolling action results in a curve being imparted to each card which not only tends to prevent the ready and proper filing thereof, but also increases the necessary drawer space in 10 a filing cabinet instead of conserving the same.

15 Among the several objects of my invention are to provide a typewriting machine in which each card will be retained in its flat condition while it is in the machine and thereby avoid the objections above noted; to 20 provide such a machine with a flat platen on which the card is supported in flat condition during printing operations; to provide type carriers each having flat upper and lower case types arranged at an angle to each other; 25 to provide means for normally supporting the platen in a plane parallel to the printing face of the lower case type when the latter is in printing position; and to provide means for moving the platen into parallelism with 30 the face of the upper case type when the latter is in printing position and for elevating the platen together with the card whereby the same printing line on the card will be presented to the upper case type.

35 In the drawings:

Figure 1 is a vertical sectional view of a typewriting machine constructed in accordance with my invention;

Figure 2 is an enlarged horizontal sectional 40 view through the flat platen and supporting frame therefor;

Figure 3 is an enlarged perspective view 45 of one of the type heads and showing particularly the angular relation between the flat upper and lower case types;

Figure 4 is a front elevation of the platen and the platen-supporting frame; and

Figure 5 is a vertical sectional view thereof.

50 Referring to the accompanying drawings,

the machine includes generally a main frame A, a shift frame B, a carriage C, an escape- 65 ment mechanism D for the carriage, a segment E supported on the main frame, a plu- rality of type carriers F, and a key lever G for actuating the type carrier.

The main frame includes side plates 5 which are formed with downwardly extending 60 passages or slots 6 arranged in register in a transverse plane directly in rear of the segment E.

A flat platen H is supported on a flat plat- 65 en-supporting frame J which is secured in- 70 termediate its upper and lower ends to a hor- 75 izontal rock shaft 7 which is journaled in the end plates 8, 8 of the carriage C. The platen frame J includes a back 9 and for- 80 wardly extending side flanges or guides 10, 10. The platen H includes a plate 11 having forwardly extending side flanges or guides 12, 12 having undercut side faces 13, 13, and 85 between which is removably mounted a flat unit comprising an outer layer 14 of rubber or the like for receiving type impacts and an inner layer 15 of lead, composition, fibre, or 90 other sound deadening material, said layers being secured together preferably by vulcan- 95 izing. The platen H is mounted against the back 9 of the frame J and between the guide flanges 10, 10 thereof. A series of anti-fric- 100 tion balls 16 is located in raceways 17 which are formed partly in each flange 10 of the frame J and the adjacent flange 12 of the platen and function to permit the platen H to be moved vertically relative to the frame J for line spacing purposes by mechanism which is not disclosed in this application.

Surrounding each ball 16 is a gear 16a which is bodily movable with the ball, and is 90 in constant engagement with racks 16b and 16c respectively fixed to the platen H and platen-supporting frame J.

The platen is capable of being readily re- 95 moved from the frame by sliding the same upwardly and out of engagement with the platen frame J.

The platen H and the platen-supporting frame J are normally disposed in a plane ex- 100 tends upwardly and rearwardly, with the lower portions thereof disposed directly in

rear of the segment E and in register with the passages or slots 6 of the main frame so as to permit the platen and its supporting frame to pass through the side walls 5 of the main frame when the carriage is moved in opposite directions.

The platen H and its supporting frame J are capable of being swung about the pivot 7 and this movement is limited by front and rear stops 18 and 19 which are supported on the side plates 5 of the main frame.

A flat card 20 is supported against the front face of the platen H by a spring clip 21 which is pivoted to the upper end of said platen, and consequently when the platen is moved upwardly for line spacing purposes the card will be moved therewith.

The plate 11 of the platen H is provided with a transversely disposed and forwardly extending projection 11a constituting a guide for the upper edge of the work sheet 20 whereby the sheet may be readily squared with respect to the platen and type when the latter is in printing position.

Each type carrier F comprises a type bar 22 which is pivoted to the segment E as at 23, and includes a head 24 having flat upper and lower case types 25 and 26 respectively, whose printing faces are in planes at an obtuse angle to each other. The printing face of the lower case type 26 is disposed in parallelism with the longitudinal axis of the type bar. The type bars in their normal positions are supported by a head rest 27 attached to the main frame. Each type bar, during its printing stroke, is swung upwardly and rearwardly to the vertical plane containing the axis 23 of the type bar, and thence rearwardly and downwardly into printing engagement with the platen H. The platen is normally upwardly and rearwardly inclined as shown in full lines in Figure 1 and is therefore normally disposed in parallelism with the printing face of the lower case type 26 when the latter is in printing position, while, at this time, the printing face of the upper case type 25 is in a plane at an acute angle to the platen and consequently the upper case type will not print when the lower case type is printing.

The angular relation between the printing faces of the upper and lower case types is indicated in Figure 1 by the lines s—s and t—t, and the angle thus formed is identical with the angle formed by the impression surface of the platen H when the platen is in its extreme positions.

The specific type bar action is disclosed in my Patent 1,390,708, of September 13, 1921, and includes a front link 28 pivoted on a wire 29, a link 30 pivotally connecting the front link and the heel of the type bar, the key lever G, a link 31 pivotally connecting the front link with said key lever, a return spring

32 for the key lever, and a return spring 33 for the type bar.

In order to actuate the escapement mechanism D each time a key lever G is depressed, I have pivoted a universal bar or frame 34 on the front link pivot wire 29. This universal bar or frame consists of two end plates 35, 35 and upper and lower tie rods 36 and 37. The upper tie rod 36 also serves as an impact rod against which each front link 28 engages during its travel to actuate the type bar. Each front link 28 is provided with a projection 38 which, after the link has completed a part of its travel, contacts the rod 36 to thereby actuate the universal bar 34. Pivotally connected to the tie rod 37 is the forward end of a rearwardly extending link 39 which is pivotally connected at its rear end to the upper end of a vertical lever 40 fulcrumed intermediate its ends as at 41 to the main frame. The lower end of the vertical lever 40 is pivotally connected to the forward end of a rearwardly extending link 42 and the rear end of this link is pivotally connected to the lower end of a lever 43 which is fulcrumed intermediate its ends on the main frame. A spring 44 which is connected to the lever 43 and to the main frame functions to return the universal bar 34 to its initial position. The lever 43 is normally disengaged from a lever 45 which actuates the escapement D. When a key lever G is depressed the front link 28 will actuate the universal bar 34 and consequently the lever 43 which in turn will engage the lever 45 and thereby actuate the escapement.

When it is desired to print with the upper case type 25 it is necessary to swing the platen H into the dotted line position shown in Figure 1 and thereby position the platen in parallelism with the printing face of said upper case type, and, in order that the upper case type will print on the same printing line on the card 20 as the lower case type, it is necessary to elevate the platen. To this end I have provided a shift key lever 46 and connections between said lever and the platen and other connections between said lever and the carriage whereby the above movements to the platen will be effected.

The shift key lever 46 is provided with an upstanding arm 47 which is connected by a link 48 to the upper end of a vertical lever 49 fulcrumed intermediate its ends as at 50 to the main frame. The lower end of the lever 49 is pivotally connected to the front end of a rearwardly extending link 51 which is centrally connected by a pin and slot connection 52 to the lower end of a vertical arm 53 of a bell crank lever 54 which is fixed to a rock shaft 55 journaled in the side plates 5 of the main frame. The bell crank lever includes a rearwardly extending arm 56 to which one end of a rod 57 is connected, the other end of the rod being connected to an

5 arm which is not shown but which is similar to the arm 56, and which is fixed to the rock shaft 55. A rock shaft 58 is disposed in rear of the platen-supporting frame J and is journaled in the end plates 8, 8 of the carriage. Fixed to each end of the rock shaft 58 is a lever arm 59, and a roller 60 is journaled on the upper end of each arm and engages a slot 61 formed in a bracket 62 secured 10 to the adjacent side edge of the support J, the major axis of the slot extending in parallelism with the support. Fixed to the rock shaft 58 is a rearwardly extending arm 63 to which the upper end of a vertically disposed thrust link 64 is pivotally connected. The lower end of the thrust link 64 is provided with a fork 65 which straddles the rod 57. A forwardly extending guide 66 fixed to the carriage C receives the thrust link 64 15 and not only guides the same during endwise movement thereof but also serves to assist the arm 63 in moving the link bodily with the carriage during feeding and return movements thereof.

25 The rear end of the link 51 is pivotally connected to the lower end of a vertical lever 67 which is centrally pivoted as at 68 to the main frame of the machine. The upper end of the lever 67 is pivotally connected by a 30 link 69 to the shift arm 70 of the shift frame B, the shift arm being pivoted as at 71 to the main frame. Thus, whenever the shift key lever 46 is depressed, the carriage C will be elevated, and the platen H will be swung 35 forwardly into parallelism with the printing face of the upper case type 25.

From the foregoing it will be apparent that a card may be positioned on the flat platen and retained thereon in flat condition during 40 the entire period the card is in the machine; that when the platen is in its normal position and a key lever is depressed the type bar will be swung upwardly to a vertical plane containing the pivot of the type bar and thence downwardly and rearwardly to printing 45 position where the printing face of the lower case type will be in parallelism with the platen and the upper case type will be at an acute angle thereo; that upon depression of the key lever the escapement mechanism will be actuated and the carriage moved in letter space direction; that, when it is desired to print upper case type, the shift key 50 lever is depressed (1) to swing the platen forwardly into a position whereby said platen will parallel the printing face of the upper case type when the latter is in printing position and whereby the lower case type will be at an acute angle to the platen, and (2) to 55 elevate the carriage and platen whereby the same printing line on the card will be presented to the type.

I claim:

65 1. In a typewriting machine, the combination with a type carrier, of flat types mount-

ed on said carrier and having printing faces disposed at an angle to each other, a flat platen normally disposed in a plane parallel to the printing face of one type when said type is in printing position and movable into another plane disposed in parallelism with the printing face of the other type when said other type is in printing position, and means for moving the platen from one position to the other. 75

2. In a typewriting machine, the combination with a type carrier, of flat upper and lower case types mounted on said carrier and having printing faces disposed at an angle to each other, a flat platen normally disposed in a plane parallel to the printing face of the lower case type when said lower case type is in printing position and movable into another plane disposed in parallelism with the printing face of the upper case type when said upper case type is in printing position, and means for moving the platen from one position to the other. 80

3. In a typewriting machine, the combination with a type carrier, of flat upper and lower case types mounted on said carrier and having printing faces disposed at an angle to each other, a flat platen normally disposed in a plane parallel to the printing face of the lower case type when said lower case type is in printing position and movable into another plane disposed in parallelism with the printing face of the upper case type when said upper case type is in printing position, and means for moving the platen from one position to the other and for elevating the platen to present the same printing line of the platen to the upper case type. 90

4. In a typewriting machine, a flat platen normally inclined rearwardly, a type carrier movable in a fixed path from a position of rest to printing position, flat types mounted on said carrier and having printing faces which are disposed at an angle to each other, one of said faces being disposed in parallelism with the platen and the other being disposed at an angle to the platen when said one face is in printing position, and means for changing the angle of inclination of the platen to parallel the other type face when the latter is in printing position. 105

5. In a typewriting machine, a flat platen normally inclined rearwardly, a type carrier movable in a fixed path from a position of rest to printing position, flat types mounted on said carrier and having printing faces which are disposed at an angle to each other, one of said faces being disposed in parallelism with the platen and the other being disposed at an angle to the platen when said one face is in printing position, and means for changing the angle of inclination of the platen and for elevating the platen to present the same printing line of the platen to the other type face whereby the 110

120

125

130

latter will be in parallelism with the platen when in printing position.

6. In a typewriting machine, a flat platen normally inclined rearwardly, a segment located in front of the platen, type bars pivoted to said segment, and flat types mounted on each type bar and having printing faces which are disposed at an angle to each other, one of said faces being disposed in parallelism with the platen and the other being disposed at an angle to the platen when said one face is in printing position, and means for changing the angle of inclination of the platen to parallel the other type face when the latter is in printing position.

7. In a typewriting machine, a flat platen element normally inclined rearwardly, a segment element located in front of the platen, type arms pivoted to said segment, flat upper and lower case types mounted on each type bar and having printing faces which are disposed at an angle to each other, the printing face of the lower type being disposed in parallelism with the platen element and the face of the upper type being disposed at an angle to the platen element when said one face is in printing position, and means for changing the angle of inclination of the platen element and for elevating one of said elements to present the same printing line thereof to the upper case type and in parallelism with the printing face of said type when the latter is in printing position.

8. In a typewriting machine, a flat platen normally inclined rearwardly, a segment located in front of the platen, type arms pivoted to said segment, flat upper and lower case types mounted on each type bar and having printing faces which are disposed at an angle to each other, the printing face of the lower type being disposed in parallelism with the platen and the face of the upper type being disposed at an angle to the platen when the lower type face is in printing position, and means for changing the angle of inclination of the platen and for elevating said platen to present the same printing line thereof to the upper case type and in parallelism with the printing face of the upper type when the latter is in printing position.

9. In a typewriting machine, a flat platen normally inclined rearwardly, a type carrier movable in a fixed path from a position of rest to printing position, flat types mounted on said carrier and having printing faces which are disposed at an angle to each other, one of said faces being disposed in parallelism with the platen and the other being disposed at an angle to the platen when said one face is in printing position, and means including a key lever and connections between the lever and the platen for changing the angle of inclination of the platen to parallel the other type face when the latter is in printing position.

10. In a typewriting machine, a flat platen normally inclined rearwardly, a type carrier movable in a fixed path from a position of rest to printing position, flat types mounted on said carrier and having printing faces which are disposed at an angle to each other, one of said faces being disposed in parallelism with the platen and the other being disposed at an angle to the platen when said one face is in printing position, and means including a key lever and connections between the lever and the platen for changing the angle of inclination of the platen and for elevating the platen to present the same printing line of the platen to the other type face whereby the latter will be in parallelism with the platen when in printing position.

11. In a typewriting machine, the combination with a segment, of a plurality of type bars pivoted thereto, a flat platen disposed in rear of the segment and fulcrumed on a horizontal axis normally located centrally between the upper and lower edges of the platen, said platen being normally inclined upwardly and rearwardly and having its lower portion disposed directly in rear of the segment, flat types mounted on each type bar and having printing faces which are disposed at an angle to each other, one of said faces being disposed in parallelism with the platen and the other being disposed at an angle to the platen when said one face is in printing position, and means for swinging the platen about its fulcrum and into parallelism with the other type face when the latter is in printing position and for elevating said platen to present the same printing line thereof to said other type face.

12. In a typewriting machine, the combination with a main frame, of a shift frame mounted on the main frame for vertical movements, a carriage supported on the shift frame for letter space movements, a flat platen rockable about a horizontal axis on the carriage, a plurality of type bars pivoted on the main frame, upper and lower case type mounted on each type bar and disposed at an angle to each other, the platen being normally upwardly and rearwardly inclined and in parallelism with the printing face of the lower case type when the latter is in printing position, and means for raising the shift frame and for swinging the platen whereby the platen will be disposed in parallelism with the printing face of the upper case type when the latter is in printing position and for presenting the same printing line of the platen to said upper case type.

13. In a typewriting machine, the combination with a platen-supporting frame, of a flat platen slidably mounted in said frame, a type carrier having flat types whose printing faces are disposed at an angle to each other, one of said faces being disposed in parallelism with the platen and the other being dis-

posed at an angle to the platen when said one face is in printing position, said platen being normally disposed in parallelism with the printing face of one of the types when 5 the latter is in printing position and at an angle to the printing face of the other type, and means for elevating the platen and the platen-supporting frame and for changing the angle of inclination to position said platen 10 in parallelism with the printing face of said other type and for positioning the same printing line of the platen to the printing face of said other type.

14. In a typewriting machine, the combination with a main frame, of a shift frame mounted on the main frame for vertical movements, a carriage supported on the shift frame for letter space movements, a flat platen rockable about a horizontal axis on the 20 carriage, a plurality of type bars pivoted on the main frame, upper and lower case type mounted on each type bar and disposed at an angle to each other, the platen being normally upwardly and rearwardly inclined and 25 in parallelism with the printing face of the lower case type when the latter is in printing position, means for raising the shift frame and for swinging the platen whereby the platen will be disposed in parallelism 30 with the printing face of the upper case type when the latter is in printing position and for presenting the same printing line of the platen to said upper case type, and means for simultaneously elevating the carriage and 35 for swinging the platen.

15. In a typewriting machine, a flat platen normally inclined rearwardly, a segment located in front of the platen, type arms pivoted to said segment, flat upper and lower 40 case types mounted on each type bar and having printing faces which are disposed at an angle to each other, the printing face of the lower type being disposed in parallelism with the platen and the face of the upper 45 type being disposed at an angle to the platen when the type is in printing position, and means for changing the angle of inclination of the platen and for elevating said platen to present the same printing line thereof 50 to the upper case type and in parallelism with the printing face of the type when the latter is in printing position, the platen being normally inclined rearwardly in both lower and upper case printing positions.

55 16. In a typewriting machine, a carriage having end plates, a flat platen disposed between and pivoted to said end plates, and means for swinging the platen including slotted plates movable with the platen during 60 pivotal movements thereof, a rock shaft journaled on the end plates, arms fixed to the rock shaft and engageable in the slots of the plates, and means for oscillating said rock shaft.

65 17. In a typewriting machine, the combi-

nation with a main frame, of a carriage mounted thereon for letter space movements, a flat platen normally inclined rearwardly, means for pivotally supporting the platen on the carriage to swing about a horizontal axis 70 located in rear of the platen face and normally located centrally between the top and bottom thereof, a type carrier mounted on the main frame, flat types mounted on the carrier and having printing faces disposed at an angle to each other, said platen being normally disposed in a plane parallel to the printing face of one type when said type is in printing position and movable into another plane disposed in parallelism with 75 the printing face of the other type when said other type is in printing position, and means for swinging the platen from one position to the other.

In testimony whereof, I have hereunto 80 subscribed my name.

EDWARD B. HESS.
